(57) **CLAIM**

The ornamental design for mobile solar array, as shown and described.

DESCRIPTION

FIG. 1 is a top and side perspective view of a mobile solar array showing my new design;

FIG. 2 is a side elevation view thereof;

FIG. 3 is a side elevation view thereof, shown from the opposite side of FIG. 2;

FIG. 4 is a front elevation view thereof, the rear elevation view being a mirror image;

FIG. 5 is a top plan view thereof; and,

FIG. 6 is a bottom plan view thereof.

The trailer shown in broken lines represents unclaimed subject matter and forms no part of the claimed design.
